UNITED STATES PATENT OFFICE.

JOSEPHINE RUSSELL, OF TABOR, IOWA.

DESIGN FOR A BADGE.

SPECIFICATION forming part of Design No. 33,624, dated December 4, 1900.

Application filed November 3, 1900. Serial No. 35,425. Term of patent 7 years.

To all whom it may concern:

Be it known that I, JOSEPHINE RUSSELL, a citizen of the United States, residing at Tabor, in the county of Fremont and State of Iowa, have invented and produced a new and original Design for Badges, of which the following is a specification, reference being had to the accompanying drawings, forming a part hereof.

10 Figure 1 is a front elevation of my design. Fig. 2 is a vertical section on line 2 2 of Fig. 1, and Fig. 3 is a side view of Fig. 1.

As shown in the drawings, the design consists of a blade or body portion 1, of substantially uniform thickness, having lower sharp corners and upper rounded corners. The center of the body portion is provided with a circular panel 2, raised beyond the plane of the outer face of the blade, the latter being

provided within the panel with a pocket 3, 20 depressed below the plane of the outer face of the blade, said pocket being provided with a disk bearing a portrait 4. Disposed along the front face of the blade and terminating at the panel 2 is a rib 5, which after it leaves 25 the blade curves rearwardly and thence downwardly in the form of a tapering pin 6.

Having described my invention, what I claim is—

The design for a badge as herein shown and described.

In testimony whereof I affix my signature in presence of two witnesses.

JOSEPHINE RUSSELL.
